ROTARY DISK SHARPENER

William A. Frusher, Ness City, Kans.

Application February 14, 1950, Serial No. 144,178

3 Claims. (Cl. 51—248)

1
This invention comprises novel and useful improvements in a rotary disk sharpener and more specifically pertains to an improved sharpening attachment which may be readily applied to the frame of a rotary disk cultivator for sharpening the edges of the rotary disks during operation of the implement.

The primary object of this invention is to provide an improved attachment which may be readily applied to all conventional types of rotary disk cultivators for sharpening the disks thereof.

A further object of the invention is to provide an attachment in conformity with the foregoing object wherein the sharpener may be adjusted to impart predetermined beveled edges at various selected angles with respect to the axis of rotation of the disks.

Still another important object of the invention is to provide an improved sharpening attachment for rotary disks of disk cultivators which may be readily adjusted to accommodate different sizes of disks; wherein bevels may be abraded on the edges of disks at predetermined angles with respect to the axis of rotation of the same; and wherein the abrading element of the sharpener may be applied against the beveled edge of a disk with a predetermined and easily adjusted resilient pressure.

Still another important object of the invention is to provide an improved sharpening attachment in conformity with the foregoing objects wherein in the rotation of the disks of the disk cultivator during normal operation or use of the same may be relied upon to impart rotation to an abrasive wheel carried by the sharpener and for effecting an abrading action uniformly about the beveled edge of a disk.

These, together with various ancillary features and objects of the invention, which will later become apparent as the following description proceeds, are attained by the present invention, a preferred embodiment of which has been illustrated by way of example only in the accompanying drawings, wherein:

Figure 1 is a fragmentary top plan view showing a portion of a rotary disk cultivator having the improved sharpening attachment forming the subject of this invention applied thereto;

Figure 2 is a vertical transverse sectional view taken substantially upon the plane indicated by the section line 2—2 of Figure 1 and illustrating the manner in which the sharpener is applied to a disk cultivator frame for sharpening the beveled edges of a rotary disk of the same;

2
Figure 3 is a fragmentary rear elevational view of the embodiment of Figure 1;

Figure 4 is an end elevational view showing the abrasive wheel and its support which forms an element of this invention;

Figure 5 is a perspective view showing a clamping element forming a part of the invention;

Figure 6 is a perspective view of another clamping element by means of which the abrasive wheel support is secured to a mounting arm forming a part of the invention;

Figure 7 is a fragmentary perspective view showing the manner in which the supporting arm is pivotally and adjustably secured to a standard forming a part of the invention; and

Figure 8 is a perspective view of an adjustable brace element forming a part of the invention.

Referring now more specifically to the accompanying drawings, wherein like numerals designate similar parts throughout the various views, it will be seen that numeral 10 indicates generally a portion of the frame of an agricultural implement which in accordance with conventional practice has journaled therebeneath an axle 12

25 provided with a plurality of cultivating disks 14, all of a conventional and known design. As is well understood by those skilled in the art, each of the disks 14 is provided with a beveled rim 16 constituting a knife edge which is employed to cultivate the ground as the implement is dragged thereover by any suitable towing means such as a tractor or the like. Since during usage the beveled edges 16 of the disks 14 customarily become dull by virtue of their engagement with the soil, rocks or the like, it is necessary at more or less frequent intervals to sharpen the disks by grinding or abrading the beveled edges 16 to again restore them to a circular knife edge.

The present attachment which forms the subject of this invention, therefore, aims to provide a sharpening means which may be easily mounted upon the framework 10 or removed therefrom, and which may be readily adjusted to utilize the rotation of the disks during normal operation of the cultivator to effect the desired abrading action upon the beveled edges 16 for restoring their sharpness.

For this purpose, there is provided a mounting means to adjustably attach the sharpening device to the frame 10. This mounting means includes a clamping bracket 18, which as shown in Figures 2 and 5, consists of perpendicularly disposed legs 20 and 22, the former being provided with a laterally extending internally threaded boss 24 for the reception of a set screw or the like

26. The leg 22, as shown best in Figure 5, is provided with a plurality of apertures or bores 28 for selectively receiving a vertical standard 30 therein, the standard being retained as by set screws 32 disposed in suitable threaded apertures 34 in the side of the leg 22 and intersecting the bores 28.

It will now be seen by reference to Figure 2 that the leg 20 of the mounting bracket 18 slidably engages the vertically upstanding flange 34 10 of the transverse angle iron member 36 which constitutes a part of the frame 16.

It is believed apparent that by loosening the set screw 26, the bracket 18 and the standard 30 carried thereby may be adjusted longitudinally 15 of the beam 36, and by tightening the set screw 26, the standard 30 may be clamped against the opposite side of the flange 34 from the bracket leg 20, thereby securely locking the standard in adjusted position upon the angle iron member 36. 20

Slidably carried by the standard 30, and vertically adjusted thereon are a mounting means for the sharpening element and an abutment means for yieldingly urging the abrasive element against the bevel 16 of a disk 14. This mounting means, as shown best in Figures 2 and 7, consists of a sleeve or collar member 88, which loosely embraces the standard 30 and is vertically slidably thereon, it being locked in vertically adjusted position as by a set screw 48, this sleeve being pivotally secured as by a set screw or bolt 42, to the apertured end of a supporting arm 44. The arm 44 is thus pivoted for vertical movement, and likewise is adjustably vertically slidable upon the support standard 30.

A fixed abutment 46 in the form of a laterally extending plate is provided with a tubular boss or sleeve 48 which slidably embraces the standard 30, and is secured at vertically adjusted position thereon as by a set screw 50. The outer end of this abutment arm 46 is apertured and receives the upper extremity of a stem 52 whose lower end is provided with a screw-threaded engagement with a nut 54, a compression spring 56 being retained upon the stem between the lower surface of the abutment plate 46 and the nut 54, to thereby urge the latter and the stem into abutting relation with the upper surface of the pivoted support arm 44. A suitable retaining member 58 is provided upon the upper extremity of the stem 52 to prevent the latter from being withdrawn downwardly through the aperture in the abutment arm 46. Thus, the spring 56 through the nut 54 on the end of the stem 52 serves to yieldingly urge the supporting arm 44 in downward pivoted position upon its pivot pin 42.

Adjustably mounted upon the end of the support arm 44 is the sharpening element forming an essential feature of this invention. A supporting base in the form of a flat plate or the like 60 of any suitable material, size and shape, has secured to its under surface as by means of a screw-threaded stem 62, see Figure 6, and a locking nut 64, a depending mounting bracket 66 having an aperture 68 therein and a set screw 70 extending into this aperture. The aperture 68 is adapted to receive the extremity of the support arm 44, whereby the plate 60 may be mounted upon the arm in an angularly adjusted position and locked thereon as by means of the set screw 70. Secured to the upper surface of the opposite ends of the plate as by fastening bolts 72, are a pair of journal bearings 74, see Figure 4, in which is journaled an axle 76 which is thus rotatably

received in the journal 74 and is retained therein as by conventional fastening collars 78. The extremity of the axle 76 overhangs the end of the base plate 60 and is rigidly secured to an abrasive wheel 80 of any desired character.

The arrangement is such that by properly positioning the mounting bracket 18 upon the angle iron beam member 36 the abrasive wheel 80 will be disposed so as to engage one of the beveled edges 16 of a disk 14. When so engaged, the resilient means 56 will yieldingly urge the abrasive wheel against the disk. The axes of rotation of the disk 14 and the abrasive wheel 80 is such that a skew action is effected, whereby the frictional engagement of the disk and wheel will cause rotation of the wheel as the disks 14 and their axles 12 are rotated during operation of the cultivating implement. However, this rotation of the wheels 80 results in a scraping or abrasive action of the wheels upon the disk bevel 16 thereby uniformly sharpening these beveled edges during rotation of the disks.

In order to render the device more steady in its operation, a brace means is provided to render the position of the wheel more rigid with respect to the position of the disks 14. This brace means may conveniently comprise a mounting clamp 82, which may be of the same identical construction described with respect to the mounting bracket 18, and which is likewise provided with a vertically extending standard 84, see Figure 3. A sleeve 86 is slidably received upon the standard 84, being adjustably retained thereon as by a set screw 88. This sleeve is provided with a pivot pin 90, which extends through an aperture 92 in one terminal 94 of an adjustable brace.

As shown best in Figure 8, this brace comprises a pair of slidably and longitudinally extensible straps 96 and 98 having a plurality of apertures for selective engagement by wing bolts or the like 100. Thus, the overall length of the straps 96 and 98 may be varied as desired. At its other extremity the strap 98 is provided with an aperture 102 which is pivotally connected as at 104, see Figure 3, with a fastening sleeve 106 which is adjustably secured as by a set screw 108 to the supporting arm 44.

It will thus be seen that the brace is adjustable 50 so as to render the vertically pivoting support arm 44 more rigid against lateral displacement and thus to more securely retain the abrasive wheel 80 in proper engagement upon the beveled edge of the rotary disk.

From the foregoing, the construction and operation of the device together with its many advantages will be readily understood and further explanation is believed to be unnecessary. However, since numerous modifications and changes 60 will readily occur to those skilled in the art after a consideration of the foregoing specification and accompanying drawings, it is not desired to limit the invention to the exact construction shown and described, but all suitable modifications and equivalents may be restored to, falling within the scope of the appended claims.

Having described the invention, what is claimed as new is:

1. A rotary disk sharpener comprising a support, an abrasive wheel rotatably carried by said support, mounting means for attaching said support to a rotary disk frame, resilient means engaging said support and urging said wheel against the rim of a disk, brace means engaging said support and adapted for engagement with a rotary

disk frame for angularly adjusting the axis of rotation of said wheel relative to that of said disk, said brace means comprising an anchor clamp adapted to engage a rotary disk frame, an adjustable link secured to said anchor clamp and said support.

2. A rotary disk sharpener comprising a support, an abrasive wheel rotatably carried by said support, mounting means for attaching said support to a rotary disk frame, resilient means engaging said support and urging said wheel against the rim of a disk, brace means engaging said support and adapted for engagement with a rotary disk frame for angularly adjusting the axis of rotation of said wheel relative to that of said disk, said brace means comprising an anchor clamp adapted to engage a rotary disk frame, an adjustable link secured to said anchor clamp and said support, said mounting means comprising a standard, a clamp securing said standard to a rotary disk frame, a carriage slideable upon said standard for longitudinal adjustment thereon, an arm pivoted to said carriage, said support being secured to said arm.

3. A rotary disk sharpener comprising a support, an abrasive wheel rotatably carried by said support, mounting means for attaching said support to a rotary disk frame, resilient means en-

5 gaging said support, and urging said wheel against the rim of a disk, brace means engaging said support and adapted for engagement with a rotary disk frame for angularly adjusting the axis of rotation of said wheel relative to that of said disk, said brace means comprising an anchor clamp adapted to engage a rotary disk frame, an adjustable link secured to said anchor clamp and said support, the axes of rotation of said disk and wheel being inclined whereby relative rotation thereof will cause sliding of said wheel upon said disk.
